ANTIRATTLER FOR DOORS

John L. Croll and Lloyd F. Lutz,
Kansas City, Kans.

Application November 18, 1933, Serial No. 698,635

2 Claims. (Cl. 16—85)

Our invention relates to improvements in anti-rattlers for doors. It is particularly well adapted for use as an anti-rattler for automobile car doors.

5 One of the objects of our invention is to provide novel means by which the anti-rattler is retained in its operative position without the use of screws, nails or welding.

10 A further object of our invention is the provision of novel fastening means for the anti-rattler which is simple, cheap, durable, not likely to get out of order, which enables the quick fastening of the anti-rattler and its easy and ready removal, if desired, and which, when the anti-rattler is 15 mounted in a recess of irregular contour in a door or door frame tends to center the anti-rattle in the recess and retains it securely therein.

15 The novel features of our invention are hereinafter fully described and claimed.

20 In the accompanying drawing illustrative of our invention,

Fig. 1 is a reduced elevation of a portion of a car door and the jamb to which it is hinged, showing two of our improved anti-rattlers mounted in 25 the jamb.

Fig. 2 is an enlarged side elevation of our improved anti-rattler shown mounted in operative position in a door jamb, part of which is shown in vertical section.

30 Fig. 3 is an enlarged view, partly in side elevation and partly in vertical section, of our improved anti-rattler shown mounted in a part of a door jamb and provided with the filler collar.

Fig. 4 shows our improved anti-rattler reduced 35 and in side elevation and shown mounted in the rumble seat portion of a car shown in vertical section.

Fig. 5 is a reduced view partly in vertical section and partly in elevation, showing our improved anti-rattler mounted in an arcuate portion of a car door jamb.

Fig. 6 is an enlarged view, partly in elevation and partly in vertical section, showing our improved anti-rattler mounted in a car door with 45 the plunger engaging the door jamb.

Fig. 7 is an enlarged plan view of a collar having three equally spaced arms.

Fig. 8 is a section on the line 8—8 of Fig. 7.

Similar characters of reference designate similar parts in the different views.

1 designates a support or casing comprising a tube having a closed inner end provided with a hole 2 through which is reciprocative the reduced inner end portion 3 of a plunger, the enlarged outer end portion 4 of which is slidably fitted in

the casing 1 and projects from the outer end thereof. Resilient means comprising a coil spring 5 encircles the portion 3 and bears at its inner or rear end against the rear end of the casing 1, the forward end of the coil bearing against the portion 4 of the plunger, so as to normally force the latter outwardly. A cotter pin 6 extends through the portion 3 and is adapted to engage the outer side of the rear end of the casing 1 for limiting the outward forward movement of the 10 plunger. See Fig. 3.

As shown in Figs. 1, 2, 3, 4, 5 and 6, the support or casing 1 is adapted to be extended into a hole or recess provided in one of two members comprising a door and a door frame or jamb.

In Figs. 1, 2 and 3, the casing 1 is inserted into a hole 7 provided in the vertical edge of a car door jamb 8. In Fig. 4 the casing 1 is inserted in a vertical position in the recess 9 provided in the horizontal upper edge of the door jamb 10. In 20 Fig. 5 the casing 1 is shown mounted in a recess 11 in the arcuate lower corner of a door jamb 12. In Fig. 6 the casing is shown mounted in a recess 13 in the car door 14.

For retaining the casing 1 in the hole or recess 25 in which it may be mounted, whether in the door or in the jamb, we provide a member comprising a collar 15 which is adapted to encircle the casing or support 1, said member having one or more portions, preferably outwardly curved resilient 30 rearwardly extending arms 16 adapted to be inserted between and to be compressed by the casing 1 and the wall of the hole or recess into which the casing 1 extends. The arms 16 are circularly arranged and equally spaced apart so as to tend 35 to center the casing 1 in the hole or recess in which the casing is inserted. When the arms are compressed between the casing 1 and the wall of the hole or recess, they retain the casing releasably in its operative position and dispense with 40 the use of screws or nails for effecting such function.

The casing or support 1 is provided at its outer end with a circular peripheral flange 17 against which, as shown in Figs. 1, 2, 4, 5 and 6 bears the 45 collar 15, the latter in turn bearing against the adjacent member in which the casing is inserted.

As shown in Fig. 1, two anti-rattlers are provided disposed respectively above and below the lower hinge 18. When the door 19 is closed its 50 hinged edge strikes and forces inwardly the plungers 4, each of which being pressed outwardly by the coil spring 5 in the casing 1, exerts a pressure tending to force the door 19 away from the jamb 8, thus preventing rattling of the door, 55

and, when the door is opened, assisting in such opening.

In Fig. 4, the rumble seat door 20, when closed, depresses the plunger 4 against the pressure of its spring 5, thus preventing the door rattling against the jamb 9.

In Fig. 5, the door 21 in closing has its lower curved corner depress the plunger 4 against the pressure of the adjacent spring 5, whereby the door is lifted and forced away from the jamb 12.

In Fig. 6 in which the casing 1 is inserted in the hole 13 of the door 14, when the latter is closed, the plunger 4 is struck by the jamb 8 and forced inwardly against the pressure of the adjacent coil spring 5, thus forcing the door away from the jamb, preventing the door rattling and assisting in the opening movement of the door.

In cases where the space between the door and the jamb is too great to obtain proper compression of the coil spring 5, we provide a filler collar or washer 22 which encircles the casing 1 between the flange 17 and the collar 15 and which bears against the said flange and collar so as to hold the casing 1 with the plunger 4 in its proper relative position.

Various modifications of our invention, within the scope of the appended claims, may be made without departing from the spirit of our invention.

What we claim is:—

1. In an anti-rattler for doors, the combination with a support adapted for insertion into a recess in one of two cooperating members comprising a door and a door frame, a plunger reciprocative on said support, and means normally forcing said plunger to a position in which it is adapted for pushing engagement with the other of said members, of a member adapted for insertion between and to have holding engagement with said support and the wall of said recess.

2. In an anti-rattler for doors, the combination with a support having a peripheral flange and adapted for insertion into a recess in one of two cooperating members comprising a door and a door frame, a plunger reciprocative on said support, and means normally forcing said plunger to a position in which it is adapted to have pushing engagement with the other of said members, of a collar adapted to encircle said support and to abut against the member having said recess and having a portion adapted for insertion between and to have holding engagement with said support and the wall of said recess, and a filler collar adapted to encircle said support between and to bear against said flange and against said first named collar.

JOHN L. CROLL.
